ANTIMACASSAR

John Hughes, Jr., Milwaukee, Wis., assignor to Enger-Kress Company, West Bend, Wis., a corporation of Wisconsin

Application May 5, 1954, Serial No. 30,332

Term of patent 3½ years

(Cl. D92—26)

To all whom it may concern:

Be it known that I, John Hughes, Jr., a citizen of the United States, residing at Milwaukee, Wisconsin, in the county of Milwaukee and State of Wisconsin, have invented a new, original, and ornamental Design for an Antimacassar, of which the following is a specification, reference being had to the accompanying drawing, forming part thereof.

The figure is a plan view of the antimacassar, the material being thin and transparent so that the same design effect shows from the other side.

I claim:

The ornamental design for an antimacassar, substantially as shown and described.
